[57] CLAIM

The ornamental design for a pocket underwear, as shown and described.

DESCRIPTION

FIG. 1 is a front elevational view of the pocket underwear showing our new design;

FIG. 2 is a rear elevational view thereof, the broken lines showing the indicia being for illustrative purposes only and forming no part of the claimed design; and the remaining broken lines on the claimed article throughout the views being understood to represent conventional stitching;

FIG. 3 is a left side elevational view thereof;

FIG. 4 is a right side elevational view thereof;

FIG. 5 is a top plan view thereof; and,

FIG. 6 is a bottom plan view thereof.
